MEANS FOR MOUNTING CURRENT-DISTRIBUTER BLOCKS.

1,292,836.

Specification of Letters Patent.

Patented Jan. 28, 1919.

Application filed October 19, 1917. Serial No. 197,442.

To all whom it may concern:

Be it known that I, SAMUEL C. McKEOWN, a citizen of the United States, residing at East Orange, in the county of Essex and State of New Jersey, have invented certain new and useful Improvements in Means for Mounting Current-Distributer Blocks, of which the following is a specification.

The object of this invention is to provide means of mounting a distributer block on an ignition apparatus, as for example a magneto, in such a way that the block will be held securely in place, at the same time permitting the holding on means to be quickly removed so that the block can be taken off the ignition machine for the purpose of inspection, etc.

There have been numerous arrangements proposed and used in the past for holding distributer blocks on to ignition devices but where such ignition devices are placed on multi-cylinder engines used in connection with hydro and aeroplanes it has been found that, due to the excessive vibration, the means used heretofore for holding the distributer blocks on ignition apparatus, such as magnetos, has been found to be inadequate; as it has been determined in actual service that wherever there is a chance for the slightest movement of the distributer blocks, that they begin to wear and in a short time become so loose on their fittings or supports as to require replacement sometimes of the whole machine, due to the fittings themselves becoming loose and worn.

My present invention is directed to ways and means of holding distributer blocks on ignition machines used in the service above described. I aim to mount the block on the supporting plate so that there is no radial movement, no longitudinal and no transverse motion and I provide means for securing the holding means so that they cannot possibly get out of normal working position, all of which will be hereinafter pointed out.

In the drawing, Figure 1 illustrates a side elevation of a magneto showing the distributer block in working position with a part of the holding means in view.

Fig. 2 is an end elevation of Fig. 1.

Fig. 3 is an enlarged perspective section of the block and support plate at the location of one of the holding means as shown in Fig. 1 but with the spring member re-

moved, and an alternative method for holding the distributer block to the support plate.

Fig. 4 is a detail view of one of the resilient members used for holding the block in working position on the magneto.

Referring now to the details, in which like numbers refer to corresponding parts in the various views, 1 is a magneto having end plates 2 and 3 which are held together by any suitable means such as bolts, one of which is shown at 4. On the end plate 2 a distributer block 5 is adapted to be mounted. Holes 6 are shown in the block 5 for the purpose of bringing out the secondary leads running to the spark plugs. Attached to the end plate 2 is a resilient member shown in Fig. 4 in the form of a flat spring 7, one end of which is turned over at 8 to receive a pin 9 that is suitably mounted in the end plate 2. The spring 7 has a bow 10 in order to give considerable resiliency to the outer end which has a hole 11, preferably oblong. The plate 2 has a rim 12, shown in Fig. 3, and the block 5 has an annular shoulder 13 adapted to closely fit under the rim 12, thus preventing radial motion of the block. Securely fastened to the block 5 are studs 14 preferably of metal and rectangular in shape and terminating in projections 15 somewhat conical or acorn shaped, that is to say, the ends 15 have grooves 16 slightly smaller than the ends 15 so that the holes 11 in spring members 7 will snap over the ends 15 into the grooves 16 and due to the tension produced by the bend 10 in springs 7 the resilient members will maintain a strong longitudinal pull. The lugs 14 enter rectangular shaped slots 17 in the ears 18 that project outwardly from the support plate 2 along the sides of distributer block 5. The ears 18 thus serve as support guides for block 5 and with the rim fit previously described serve to prevent any transverse motion of the block. By transverse motion I mean motion at right angles to the ears 18. The exact size and shape of the slots 17 and the studs 14 may be varied considerably from that shown so long as they coöperate to absolutely prevent any rotary movement of the block 5.

Attached to the ears 18 are bosses 19 through 20, which the cotter pin 20 is adapted to pass, the same being put into position as shown in Fig. 1 after the spring members 7 are

snapped into working position, as shown in Fig. 2. The pins 20 thus serve to prevent the springs 7 from snapping off the stud ends 15.

5 It will thus be seen that I have provided means for preventing longitudinal, transverse, radial and rotary motion of the block and have provided means for fastening the retaining springs so that they cannot vibrate 10 out of position.

While I have shown one method of holding the spring 7 in position, it will be apparent that other means may be provided, or in some cases the springs 7 may be dispensed 15 with entirely by using pins 21, shown in Fig. 3, which can be readily removed for taking off the block 5. In this modified construction the pins 21 pass through the ears 18 and the lugs 14. As a further precaution 20 to hold the block 5 securely in place a combination of the springs 7 and pins 21 may be used so that if the springs 7 should break for any reason the pins 21 will still hold the block 5 in position. Various other changes 25 and alterations may be made in the details relating to my invention without departing from the spirit of the same or the scope of the appended claims.

Having thus described my invention what 30 I claim is:—

1. In combination a distributor block having studs thereon, a plate to receive said block, ears on said plate extending over the side of said block and adapted to engage said 35 studs, springs fastened to said plate and extending outwardly along the surface of said ears and engaging said studs for the purpose described.

2. In combination a distributor block having studs securely fastened thereto, a plate to receive said block, ears on said plate projecting over the side of said block, slots in said ears to receive said studs, springs fastened to said plate and extending outwardly 45 along the surface of said ears and engaging said lugs as described.

3. In combination a distributor block having studs securely fastened thereto, a plate to receive said block, ears on said plate projecting over the side of said block, rectangular shaped slots in said ears, said studs having a rectangular body portion to fit in said slots and acorn shaped ends, springs pivotally mounted on said plate and extending 55 outwardly to engage said stud ends as and for the purpose described.

4. In combination, a distributor block having studs securely fastened thereto, said studs having a body portion with two flat 60 sides and acorn shaped ends, a support to receive said block, ears on said support extending outwardly over the side of said block, slots in said ears of substantially the same width as the body portion of said studs 65 between the two flat faces, resilient members

fastened to said plate and having means for engaging said acorn ends to hold said block securely to the plate.

5. In combination, a distributor block having studs securely fastened thereto, said studs having a body portion with two flat sides and acorn shaped ends, a support to receive said block, ears on said support extending outwardly over the side of said block, slots in said ears of substantially the same width as the body portion of said studs between the two flat faces, resilient members fastened to said plate and having means for engaging said acorn ends to hold said block securely to the plate, and means for preventing said resilient members from working off said stud ends. 75 80

6. In combination, a distributor block having studs securely fastened thereto, said studs having a body portion with two flat sides and acorn shaped ends, a support to receive said block, ears on said support extending outwardly over the side of said block, slots in said ears of substantially the same width as the body portion of said studs between the two flat faces, bosses on said ears, resilient members pivotally fastened to said support and adapted to be turned so as to pass between said bosses and to engage said stud ends to hold said block in place 85 90 95

7. In a mounting for current distributor blocks, the combination of a supporting plate having a rim and ears projecting therefrom, a block of insulating material having current distributing contacts suitably disposed therein and studs extending outwardly from its sides with an annular shoulder at the rear to closely fit within said rim, slots so formed in said ears to receive said studs as to prevent turning of the block, and resilient members attached to said supporting plate to hold said block securely in operative position on the plate. 100 105 110

8. In a mounting for current distributor blocks, the combination of a supporting plate having a rim and ears projecting therefrom, a block of insulating material having current distributing contacts suitably disposed therein and studs extending outwardly from its sides and an annular shoulder at the rear to closely fit within said rim, said studs being rectangular in shape and terminating in conical ends, rectangular slots in said ears to receive said studs, bosses on said ears, resilient members attached to said support plate and adapted to normally lie between said bosses 115 120 125 and having holes therein to engage said conical stud ends, and pins passing through said bosses but in front of said resilient members to prevent the same from coming off said stud ends. 130

9. In a mounting for current distributor blocks, the combination of a supporting plate having a rim and ears projecting therefrom, a block of insulating material having current distributing contacts suitably disposed therein and studs extending outwardly from its sides with an annular shoulder at the rear to closely fit within said rim, said ears serving as guide supports for said block and having rectangular slots to receive said studs which project beyond said ears, flat spring members pivotally mounted to said support plate and adapted to swing outwardly to engage said 15 stud projections, and means on said plate to engage the said flat springs to prevent their coming off said projecting studs.
10. In a mounting for current distributor blocks, the combination of a supporting plate having ears projecting laterally therefrom, a block of material having current distributing contacts suitably insulated and disposed therein, studs rigidly fastened to said block, slots in said ears to receive said 25 studs, said studs and slots coöperating to effectually prevent any rotary movement of said block and resilient members attached to said plate to engage the ends of said studs to hold the block in longitudinal working position and means to prevent said resilient members from getting out of working position on said studs.
11. In a mounting for current distributor blocks, the combination of a supporting plate having ears projecting laterally therefrom, a block of material having current distributing contacts suitably insulated and
- disposed therein, studs rigidly fastened to said block, slots in said ears to receive said 40 studs, said studs and slots coöperating to effectually prevent any rotary movement of said block, and means coöperating with said ears and studs to hold the block in longitudinal working position.
12. In combination a distributor block 45 having studs thereon, a plate to receive said block, ears on said plate extending over the sides of said block and adapted to engage said studs, and means held in working position by said ear members and engaging 50 said studs for holding said block onto said plate.
13. In combination a distributor block having studs thereon, a plate to receive said block, ears on said plate having slots to receive said studs, and means held in working 55 position by said ear members and engaging said studs for holding said block onto said plate.
14. In a mounting for current distributor blocks, the combination of a supporting plate having a rim and ears projecting therefrom, a block of insulating material having current distributing contacts suitably disposed therein and studs extending 65 outwardly from its sides with an annular shoulder at the rear to closely fit within said rim, slots so formed in said ears to receive said studs as to prevent turning of the block, and means held in position by said 70 ears and engaging said studs to hold said block securely in operative position.

In witness whereof I affix my signature.
SAMUEL C. McKEOWN.
